UNITED STATES PATENT OFFICE

FRANK TENCH, OF LONDON, ENGLAND, ASSIGNOR TO AUTOMATIC ELECTRIC INC., OF CHICAGO, ILLINOIS, A CORPORATION OF DELAWARE

TELEPHONE SYSTEM

Application filed February 27, 1926, Serial No. 91,050, and in Great Britain June 4, 1925. Renewed July 26, 1928.

The present invention relates to telephone systems and as regards its main features is more particularly concerned with the operation of small exchanges on what is known as the satellite principle, by which is meant that the small exchanges have their first numerical switches located in a main exchange and thus do not themselves require so many switching stages as are needed for a full sized exchange, in many cases subscribers' line switches and connectors being sufficient.

The conditions of working are complicated somewhat in case the system employs register translators, for instance of the "director" type, the main principles of operation of which are disclosed in the British Patent No. 194,580, issued March 15, 1923. In such systems exchange selection is usually effected by dialling the first three letters of the exchange name, the dial being provided with letters as well as numerals for this purpose, and it is generally desirable for satellite exchanges to have separate names of their own in order to facilitate the change-over when the satellite grows to such a size as to warrant its conversion into a main exchange. It is probably also desirable that no register translation shall be located at the satellite, both for reasons of first cost and also because of the additional maintenance involved and it will, therefore, be arranged that a subscriber calling from the satellite will take into use a register translator located in the main exchange.

Owing to the fact that the satellite has an exchange name of its own, it will not be decided until the subscriber has dialled the first three digits whether or not the call is to be a local one, that is to say, to another subscriber in the same satellite, and it is highly desirable to arrange that if this is the case, as soon as the dialling of the first three digits has determined the destination of the call, switching over shall take place at once so that subsequent digits may be dialled direct to the local switches, one or more digits being absorbed if necessary. To effect this switching over operation, it has been usual hitherto to provide number responding devices in the satellite which operate to release the trunk line to the main exchange and the apparatus oper-

ated thereat as soon as the critical number has been dialled. Inasmuch as a register translator is being used, however, and thus the number dialled is being recorded in any event, it is arranged that registration takes place on the register translator only and the switching over operation when necessary is controlled therefrom.

According to one feature of the invention in a system including satellite exchanges having their first numerical switches located in a main exchange and having calls within the satellite adapted to be completed entirely locally, the number recording device for determining whether a call shall be switched locally are located at the main exchange.

According to another feature of the invention in a telephone system employing register controllers adapted to be seized over an inter-exchange trunk line, a signal is transmitted back to the originating exchange when the complete number has been dialled.

Another feature of the invention is that in a system including satellite exchanges, the apparatus in a satellite exchange after being initially operated by a calling subscriber thereat is adapted to be controlled from the associated main exchange by modifying circuit connections at the main exchange end of the two-conductor trunk line over which the main exchange apparatus was first operated.

A further feature of the invention is that in a system having a plurality of satellite exchanges associated with a main exchange, register devices common to the various satellite exchanges and located in the main exchange are provided with means for causing circuit connections to be made characteristic of said satellite exchanges when calls are to be set up to said exchanges, so that when a subscriber in a satellite exchange calls a subscriber in the same exchange, a circuit is completed for effecting the release of the main exchange apparatus and enabling the connection to be set up independently thereof.

Still another feature of the invention is that in a telephone system employing non-numerical switches, a non-numerical switch on being seized on the initiation of a call is adapted to preselect an idle line while the ac-

tual seizure of the idle line is adapted to be effected in response to a further operation by the calling party.

A further feature of the invention is the provision of a relay chain comprising a plurality of relays adapted to operate on different margins of current in which the energizing lead is initially connected to the relay which operates on the smallest current and on the operation of any relay is connected to the relay having the next highest margin of operation.

These features and others not specifically mentioned at this point will be better appreciated from the following description of one method of carrying the invention into effect taken in conjunction with the accompanying drawings. This arrangement shows the invention applied to a register translator system of the "director" type but clearly its application is not limited to a system having these particular characteristics.

Referring now to the drawings, Figs. 1 shows a repeater R located in a satellite exchange and accessible to a calling subscriber by way of his individual line switch. From the repeater R access may be had by way of the secondary switch M to first numerical switches at the main exchange and over the secondary switch T to a toll operator's position, which is preferably also located in the main exchange. Access may also be had over the secondary switch L to local switches in the satellite itself, the repeater R in this case being cut out and battery feed taking place from the connector according to usual practice. Figures 2, 3, 4, and 5, show a register translator or "director" located in the main exchange and modified in accordance with the invention so as to control switching operations at the repeater R in the satellite. In the arrangement shown, when the trunk line extending to Fig. 2 is taken into use, the switch SS is started hunting for a free first code selector such as DS, which is arranged to respond to the first digit dialled and thereupon hunt to find a free register translator. This then responds to the remaining two digits in the exchange name and also to the numerical digits, four of which will be assumed to be employed in this system. The digits representing the exchange name are converted by the register translator into an exchange code which may comprise from one to six trains of impulses, by means of which the connection is routed to the desired exchange and the numerical impulses are subsequently sent out unchanged by the register translator.

The general method of operation of the arrangement according to the invention will first be described briefly. Suppose in the first instance that the subscriber in the satellite wishes to set up a call to a subscriber whose line is connected to any exchange

in the system except the originating satellite. It may be pointed out in passing that when a call is extended to a subscriber in a satellite connected to the same main exchange as the originating satellite, the conditions are in no way different from those which obtain when a call is extended to an outside exchange. In the present case assume that the calling subscriber's line switch seizes the repeater R. The switch M thereupon at once operates to seize a free trunk to the main exchange, while the switches L and T move their wipers into engagement with contacts associated with free outlets but do not switch through and do not seize these outlets so as to make them busy to other similar switches. When the trunk line is seized, the switch SS commences to operate and seizes a free first code switch such as DS. The subscriber may now dial the digits corresponding to the number of the wanted line whereupon the first digit operates the switch DS, which then seizes an idle register translator connected to the particular level to which it has been raised. The remaining digits are stored in the register translator which in due course sends out the required series of impulses for completing the wanted connection. When all the digits have been dialled, however, a momentary signal is sent back to the repeater R to place the apparatus there in a condition to receive supervisory signals as distinct from a setting condition in which it is adapted to receive signals for producing particular switching operations associated with the setting up of the connection.

Consider now the case in which the calling party wishes to obtain access to the toll operator, in which case he will dial the digits TOL; the initial operations, however, are the same as before up to the taking into use of a register translator and the receipt by it of the last two digits of the exchange name. When the dialling of the digits TOL is completed, however, it is determined that the call is for the toll operator's position and, therefore, will be extended by way of the switch T over a separate direct trunk rather than over the switch M, the inter-exchange trunk line, and the main exchange switches. Hence a signal is now sent back to the repeater R which has the effect of releasing the switch M and connecting up the wipers of the switch T, whereupon a signal of a suitable nature is given to the toll operator, who then attends to the calling party's requirements.

A further case remains to be considered, namely, that in which the calling party wishes to set up a connection to a subscriber attached to his own exchange, which may, therefore, be completed entirely locally. If, however, the satellite has a separate exchange name, as is assumed to be the case, it will not be determined until he has dialled the first

three digits corresponding to the exchange name that the call is destined for the satellite to which he is connected. Consequently as before a register translator is taken into use 5 and responds to the exchange digits but in this case after the first three digits have been received, a different signal is sent back to the repeater R and this causes the switch L to be connected up, while switches M and T and 10 the remainder of the apparatus operated in the repeater R are released. In every case the register translator is released as soon as it has performed the functions required of it.

The operation of setting up various types 15 of connections having been considered briefly, these connections will now be traced through in detail. In the first case it will be assumed for the sake of convenience that the wanted party's line terminates in a satellite 20 connected to the same main exchange as the originating satellite, but it will be understood that the operations are substantially the same if the connection is extended to any other exchange in the system other than the 25 local exchange. When the contacts 1, 2, 3, and 4 are seized by a calling party over his line switch, a circuit is completed over armatures 16 and 19 and their back contacts for line relay 5, which thereupon operates and 30 at armature 7 completes a circuit for release relay 9. This thereupon at armature 13 prepares a circuit for relay 33 and at armature 11 connects earth to the release trunk conductor so as to maintain the line switch operated and also to complete a circuit for the 35 left-hand winding of polarized relay 37. At armature 11 a further circuit is completed which extends over armature 17 and its back contact, armature 30 and its back contact, 40 winding of relay 21, interrupter contact and magnet 26 to battery; while at armature 12, test wiper 57 is connected to the junction of relay 21 and magnet 26 so that the switch M commences to hunt in known manner. A 45 branch of the above traced circuit for relay 21 extends over back contact and armature 24 and through relay 39 to battery so that relay 39 thereupon operates. At armatures 40 and 42 it prepares circuits for relays 43 and 50 46 and cuts out the right-hand winding of relay 37, and at armatures 40' and 41' completes circuits previously prepared at armatures 10 and 14 for starting the hunting operation of the switches L and T. It will be 55 noted that at this time no circuit is completed for relays 15 and 27 so that it is impossible for these relays to operate when their associated switches come to rest on contacts connected to idle lines. When the switch M finds 60 a free trunk line, for instance that comprising conductors 59 and 60, there will be no earth on the contact 61 engaged by wiper 57; consequently relay 21 is not longer short-circuited and operates, thereby at armatures 22 65 and 25 connecting up wipers 56 and 58, at

armature 23 opening the initial hunting circuit and feeding earth forward to wiper 57, and at armature 24 opening the initial energizing circuit of relay 39. By the operation of armatures 22 and 25, however, circuits are completed over conductors 59 and 60 for the relays 43 and 46 and accordingly these now operate, thereby at armatures 44 and 47 completing a multiple locking circuit for relay 39 over its own armature 41. The circuit for 70 relay 43 extends as follows: earth, winding of relay 43, armature 6 and its front contact, normally closed springs controlled by armature 34, front contact and armature 40, armature 22 and its front contact, wiper 56, and 75 the contact on which it is standing, conductor 59, armature 81 and its back contact, armature 97 and its back contact, winding of relay 91 to battery. Relay 91 operates in this circuit, as well as relay 43, and at armature 93 completes a circuit for switching relay 94 80 and magnet 103 in series, and at armature 92 connects test wiper 107 to the junction of relay 94 and magnet 103. The switch SS thereupon commences to hunt in known manner 85 and when test wiper 107 engages a contact which is not earthed, relay 94 operates, thereby at armatures 95, 96, 97, 99, 101 and 102 connecting up its wipers, at armature 97 also opening the circuit for relay 91; moreover at 90 armature 98 it opens the original hunting circuit and prepares a locking circuit for itself. The operation of armatures 97 and 101 completes a circuit over the normally closed springs controlled by armatures 112 and 114 95 for line relay 115. This, therefore, operates and at armature 116 completes a circuit for relay 118. This relay upon operating in its turn at armature 119 connects up earth to 100 replace that previously provided by armature 93 and at armature 120 opens a point in the release magnet circuit and prepares the impulsive circuit. All the above described operations take place before the subscriber 105 operates his dial and it may be arranged if necessary, that when they have been completed he receives dial tone so as to indicate that it is then in order for him to start impulses.

Suppose that the number of the wanted party is UNDERwood 3456, in which case the first digit dialled corresponding to the letter U would be 8. When the loop is 110 opened, relay 5 deenergizes and at armature 7 completes a circuit for relay 33, which being slow to release, remains operated throughout the train of impulses. Relay 33 at armatures 34 and 36 cuts out relays 43 and 46 and places a direct loop across the speaking conductors so as to improve the impulsive conditions, and at armature 35 completes 115 a substitute locking circuit for relay 39. The impulses are now repeated over the outgoing trunk conductors 59 and 60 by armature 8 so that relay 115 of the switch DS deener- 120

125

130

gizes correspondingly. The contacts 6 on relay 5 are provided to ensure a proper first impulse before relay 33 had had time to operate, and as will be seen, they are cut out when this operation has occurred. Each time the relay 115 in the switch DS deenergizes, an impulse is transmitted to the vertical magnet 133, which accordingly raises the wipers, 140—145 to the eighth level. Relay 123 is energized in parallel with magnet 133 throughout the train of impulses and at armature 124 prepares a circuit for stepping relay 125 which becomes operative as soon as off normal contacts 128 close. Relay 123 also operates armature 130, but this is without effect at this stage of the connection. Relay 125 upon operating, at armature 126 completes a locking circuit for itself, and at armature 127 prepares a circuit for the rotary magnet 129. When relay 123 deenergizes at the end of the train of impulses, at armature 124 a circuit is completed for the rotary magnet which advances the wipers one step and at its interrupter contact 131 opens the locking circuit for relay 125. The hunting operation of the switch DS then takes place in known manner by the inter-action of relay 125 and magnet 129 until a free register translator is encountered. Relay 132 is then no longer short circuited and operates, thereupon at armature 136 connecting earth to wiper 142 and at armature 137 opening a point in the circuit of vertical magnet 133 and preparing a circuit for repeating impulses to the register translator. At armature 134, 135, and 139 a number of control circuits are prepared which will be described subsequently. When earth is fed forward to lead 148 over wiper 142, release relay 171 is operated and at armature 172 opens the restoring circuit for the switch OCS and prepares a locking circuit over lead 174, and at armature 173 opens the circuit for the release magnet of the various switches in the register translator.

When the subscriber dials the next digit, which in the case considered is 6, six impulses are repeated by relay 5 as before, so that relay 115 is momentarily deenergized six times. Upon each deenergization the following circuit is completed: earth, back contact and armature 117, armature 120 and its front contact, armature 137 and its front contact, wiper 143, leads 149, winding of relay 152, wiper 166 of the input control switch ICS, lead 189, vertical magnet 201 to battery. By the operation of vertical magnet 201, therefore, the code switch CS, which is a vertical and rotary switch of known type arranged to respond to the second and third exchange digits, is raised to the sixth level. Relay 152 is energized in series with the vertical magnet and being slow, remains energized throughout the train of impulses. At armature 153 it completes a circuit for

slow relay 157 and at armature 154 completes a circuit which will be described shortly. At the end of the train of impulses when relay 152 releases, a circuit is momentarily completed from earth, armature 153 and its back contact, armature 159 and its front contact for magnet 162. The wipers 163—166 of the switch ICS are thus advanced one step in readiness to route the next series of impulses to rotary magnet 202. During the first train of impulses sent to the register translator, relay 123 is again operated and at armature 130 a circuit is now completed as follows: earth, resistance 100, armature 99 and its front contact, wiper 108, front contact and armature 130, armature 138 and its front contact, wiper 144, lead 150, armature 154 and its front contact, lead 155 armatures 272, 268, 264, and 261, and their respective back contacts, normally closed springs controlled by armature 262, winding of relay 256 to battery.

A short explanation may be given at this point of the arrangement of the relays 256, 257, 258 and 259. One of these relays is provided for each satellite associated with the main exchange to which connections can be set up under the control of the register translator shown. Hence it will be appreciated that in order to indicate the flexibility of the arrangement according to the invention, the extreme case had been chosen in which no less than four satellites connected to one main exchange have their exchange names beginning with the same letter or letters which appear in the same finger hole of the dial. The relays 256—259 are each individual to a particular satellite in that the contacts controlled by each relay are connected to the contacts of the switch CS on which the wipers are set when the particular exchange name is dialled. It will be assumed that relay 259 is associated with the exchange Underwood to which a connection is now being extended, while relay 258 is associated with the exchange Vanguard from which the call is being initiated. These relays are, however, arranged to operate on different margins of current, and in the arrangement shown, the relay 256 is the most sensitive and the others are less sensitive in order. Operating in conjunction with these relays are resistance such as 100 (shown in Fig. 2), which are associated with the trunk lines leading from any particular satellite; thus for one satellite the resistance 100 will be entirely absent, that is to say, there will be a direct earth connected to the front contact of armature 99.

In case a call is from the Underwood exchange, earth is extended directly to lead 155 during the second train of impulses representing the exchange name and effects the operation of all the relays 256—259 in turn. For the second satellite, i. e., the exchange Vanguard, now calling, the resistance 100 is com-

paratively low but is sufficient to prevent the operation of relay 259, while permitting that of relays 256—258. Similarly for the other two satellites progressively higher resistances are employed so that of the fourth satellite only relay 256 is able to operate and not any of the others.

10 The connection corresponding to resistance 100 is left open at the secondary switches used to extend local lines to the directors.

15 As mentioned above, since the present call is being set up from Vanguard, the resistance 100 is comparatively low so as finally to permit the operation of relay 258, but not relay 259. Hence when the circuit above traced is completed, relay 256 operates; at its armature 262 completes a locking circuit for itself to lead 174 and at its armature 261 transfers its original energizing circuit to relay 257. This 20 relay, therefore, also operates, locks up at armature 266, at armature 265 opens the locking circuit of relay 256 so that this is deenergized, and at armature 264 transfers the energizing circuit to relay 258. This then operates with similar effect, and the energizing circuit is then transferred to relay 259. As explained above, however, owing to the resistance 100, relay 259 cannot receive sufficient current to cause it to operate and consequently the final result is that relay 258 remains operated, being locked up to lead 174 over armature 273 and its back contact. Relay 258 at its armature 253 and 267 prepares circuits which will not come into use in this 35 case since the call is to be extended through the main exchange, but the operation of which will be described subsequently.

When the subscriber dials the letter D corresponding to the third digit in the wanted 40 exchange name, three interruptions are produced in the circuit of relay 5 and these are repeated, as previously described, to relay 115. Relay 115 pulses as before and consequently three impulses of current are transmitted over lead 149 through the winding of 45 relay 152, over wiper 166 now in second position and over lead 190 to the rotary magnet 202 of the switch CS. This switch accordingly advances its wipers 203—206 three steps 50 so that they come to rest in engagement with contacts 207—210. Relay 152 is energized throughout the series of impulses and on their termination deenergizes as before and completes a circuit for magnet 162 so that the 55 wipers of the switch ICS are moved into third position. Consequently when the first numerical digit is dialled, a train of three impulses is routed over lead 191 to the stepping magnet 301 of the first digit register M^1 . Similarly 60 the remaining numerical digits 4, 5, and 6 are registered on the second, third and fourth digit registers M^2 , M^3 , and M^4 . It will be assumed that the digits 863 representing the exchange name Underwood are translated by 65 the register translator into the digits 379.

It will be seen, therefore, that as soon as the switch ICS moves into third position an earth connection extends from wiper 164 and its third contact, wiper 170 of the switch OCS, lead 192, to wiper 203, bank contact 207, armature 271 and its back contact, terminal 211 on the right-hand side of the intermediate distributing frame IDF, terminal 3 on the left-hand side, and thence over conductor 223 corresponding to a train of three impulses 70 to the fifth contact in the bank of wiper 187 of the switch SCS. Moreover the following circuit is now completed: earth, wiper 164 in third position, interrupter I, back contact and armature 182, winding of magnet 183 to battery. Magnet 183, therefore, operates and upon releasing, when the interrupter contacts 75 subsequently open, advances the wipers 186 and 187 of the sender control switch SCS into engagement with their respective second bank contacts. A circuit is thereupon completed from earth on the bank of wiper 186 for the pick-up relay 175, which at armature 176 removes one of the shunts round the impulsive 80 loop extending over leads 146 and 147, at armature 177 completes a circuit for the magnet 167 of the output control switch OCS and at armature 178 connects a multiple earth to lead 148, which is, however, without effect 85 at the present time. When the interrupter contacts again open, springs 185 are opened and an interruption is accordingly produced in the outgoing loop over conductors 146 and 147. When the interrupter contacts close, 90 the impulse is terminated and the wipers 186 and 187 are advanced one step. This operation continues until three interruptions have 95 been produced in the loop whereupon at the end of the third impulse wiper 187 is advanced into engagement with the earthed fifth contact in its bank. A circuit is then 100 completed for the stop relay 179, which thereupon operates; at its armature 180 shunts the sending contact 185 so that further operations 105 of magnet 183 are ineffective for sending impulses, at armature 181 completes a locking circuit for itself and opens the circuit of magnet 167, whereby the wipers 169 and 170 are advanced one step in readiness to control the 110 sending of the next digit, and at armature 182 disconnects the interrupter I and completes a local circuit for magnet 183 which extends over the interrupter contacts 184 and wiper 186. The switch SCS, therefore, rotates automatically until wiper 186 fails to find earth, 115 whereupon the circuit of relay 175 is opened and it commences to deenergize. When it does so after its slow period the locking circuit of relay 179 is opened and it also commences to deenergize. When both these 120 relays finally fall away, impulses are again transmitted from the interrupter I to the magnet 183 over back contact and armature 182 and thus the next digit, in this case 7, is sent 125 130

out under the control of the switch SCS in a manner similar to that just described.

In view of the fact that the operation of a sending switch such as SCS is well known in the art, no further detailed description of the sending operation will be given. It will suffice to say that at the end of each train of impulses when wiper 187 finds earth, the switch OCS is advanced one step and thereupon alters the circuits so that the wipers 203—206 in turn control the sending of the exchange selecting digits, and subsequently the wipers of the digit registers $M^1—M^4$ control the sending of the numerical digits. It will be seen that the jumpering to terminal 224 from which the so-called "skip" conductor 156 extends is for the purpose of moving the switch OCS through the 4th exchange digit position since in the present case only three series of impulses are required to route the call to the desired exchange. The sending operation, it will be understood, commences as soon as the full exchange name has been dialled and will continue automatically so long as the digit registers have been operated in advance. In case, however, the subscriber should be somewhat slow to dial so that the sending out of impulses catches up with the registering, sending will be delayed by the special circuit completed for relay 179 over lead 188 and the wiper of any digit register in its normal position.

Considering now, however, the further operation of the switch ICS, as previously pointed out, at the end of each train of incoming impulses this switch is advanced one step and since it is assumed that the system is a seven digit one, one digit being received by the switch DS and six by the register translator, it will be appreciated that when the complete number has been dialled, the wipers of the switch ICS will be advanced to seventh position. Thus after the end of the last train of impulses when relay 152 releases, the usual circuit is completed over back contact and armature 153 for the magnet 162 and the wipers 163—166 are advanced one step. While relay 157 still holds up, however, earth is connected by way of wiper 163 and the seventh contact in its bank, over armature 158 to lead 151, thence over wiper 145, front contact and armature 139, and winding of relay 113 to battery, and also over wiper 165 and the seventh contact in its bank, front contact and armature 160, back contact and armature 154, lead 150, wiper 144, front contact and armature 138, armature 130 and its back contact and winding of relay 111 to battery. Relays 111 and 113 both operate at this time and at their armatures 112 and 114 disconnect battery and earth from the line conductors 59 and 60, at the same time completing a holding circuit for the line relay 115 so that this shall not deenergize. The effect at the

repeater R of the removal of battery and earth from conductors 59 and 60 is to deenergize both relays 43 and 46, whereupon the holding circuit for relay 39 is opened at armatures 44 and 47 and it deenergizes. Thereupon at armatures 40 and 42 it cuts out relays 43 and 46 and connects up the right-hand winding of polarized relay 37 for supervisory purposes, and at armatures 40' and 41' opens the circuits to the magnets 20 and 32 so as to prevent any useless stepping operation of these magnets during the remainder of the connection. When relay 157 deenergizes an instant later, the circuits for relays 111 and 113 are opened. These relays, however, are arranged to be slow-to-release, and accordingly they hold up for a short interval sufficient to endure the deenergization of relay 39 in the repeater R, which relay is only slow enough to ensure that it shall not deenergize when relay 21 pulls up. When relays 111 and 113 finally fall away, the conditions in the switch DS are restored to normal and current flows through the winding of the relay 37, but not in such a direction as to cause it to operate.

To return now to the operation of the register translator, when the wiper 170 reaches its last position after all the digits have been sent, earth is connected to lead 149 and is extended over wiper 143, front contact and armature 137, front contact and armature 120, armature 117 and its front contact, wiper 110, front contact and armature 102, normally closed springs controlled by armature 82, winding of relay 80 to battery. Relay 80 thereupon operates, at armature 82 locks itself up to the release trunk conductor 85 and at armatures 81 and 83 connects the speaking leads through, at the same time disconnecting line relay 115. This relay, therefore, deenergizes and at armature 116 opens the circuit of relay 118. Relay 118 upon deenergizing in its turn, at armature 119 removes the locking earth for relays 94 and 132 and also removes earth from lead 148, whereupon relay 171 in the register translator is released. Thereupon at armature 173 earth is connected to lead 193 so as to complete circuits for the release magnets of the switches ICS and $M^1—M^4$ which are accordingly restored to normal. Accordingly, the switches SS and DS and the register translator are released and the latter may be taken into use for setting up other connections. In the repeater, polarized relay 37 is operated by reversal of current over the speaking leads when the called party replies, and at its armature 38 connects earth to contact 4, thus completing a circuit for the calling party's meter. At the end of the conversation, when the calling party hangs up, the circuit for relay 5 is opened and it deenergizes, thereby opening the circuit of re-

lease relay 9 at armature 7, and at armature 8 opening the circuit over the out-going leads so that all the switches ahead are released in known manner. All the apparatus involved in the connection has, therefore, now been restored to normal and is available for use in completing other connections.

Consider now the case in which a subscriber in the satellite exchange Vanguard wishes to set up a toll call; he accordingly, dials the letters TOL, the numerical equivalent of which is 805. Assume furthermore that this line switch seizes the repeater R, that the switch M again selects the outgoing trunk comprising conductors 59 and 60, and that switch SS again takes into use the first code switch DS. In response to the dialling of the first digit T, the switch DS is raised to the eighth level as before and hunts to find a free register translator. Assuming for convenience that that shown in the drawings is again employed, in response to the second digit O the wipers of the switch CS are raised to the tenth level and in response to the third digit 5 they are rotated into engagement with the fifth set of contacts in this level, which are assumed to be the contacts 212-215. During the dialling of the digit O, the discriminating earth is connected up to relays 256-259 as before and consequently again relay 258 remains energized. The switch ICS is advanced between the successive series of impulses as previously described, and as soon as its wipers move into third position, the following circuit is completed: earth, wiper 164 and the third contact in its bank, wiper 170 and the first contact in its bank, lead 192, wiper 203, contact 212, armature 254 and its back contact, armature 253 and its front contact, lead 151, wiper 145, front contact and armature 139, winding of relay 113 to battery. Relay 113 upon energizing in this circuit, at armature 114 opens the circuit of relay 43 in the repeater R, leaving relays 46 and 115 held up at this time in series. Upon the deenergization of relay 43, the following circuit is completed: earth, armature 35 and its back contact, armature 45 and its back contact, front contact and armature 49, winding of relay 27, interrupter contact and rotary magnet 32 to battery. Since the switch T has preselected an idle trunk extending to the toll operator's position, there is no earth at this time connected to wiper 54. Hence relay 27 now operates; at armatures 28 and 31 connects the speaking leads through to wipers 53 and 55, at armature 29 opens the hunting circuit and connects earth forward to wiper 54 to busy the line to other switches, at armature 29' opens the hunting circuit for the switch M, and at armature 30 completes a locking circuit for itself, at the same time opening the circuit of relay 21. Relay 21 accordingly deenergizes and at ar-

matures 22 and 25 opens the outgoing loop over conductors 59 and 60 so that relay 115 is deenergized. Consequently after a short interval, relay 118 deenergizes also and at armature 119 removes earth from holding conductor 148 so that the register translator is released in the manner previously described. At the repeater R the connection of relay 43 and 46 to the outgoing trunk conductors leading to the toll operator's position causes a visual signal to be given to indicate to the operator that a subscriber is awaiting attention. She may then complete the call in known manner and with the circuits shown all the operated apparatus would be released when the calling party hung up his receiver.

It is usually desirable, however, that the operator shall have control of the release of the connection and this could be brought about in the present instance by arranging for the operator to connect earth to the upper trunk conductor thereby bringing down relay 43, and over an additional back contact on this relay and a front contact on relay 46, an auxiliary circuit could be completed for relay 9 so that the connection would remain set until its release was initiated by the operator. Alternatively, the operation of relay 27 could be arranged to open the circuit of relay 39 so that relays 43 and 46 are cut out, and the polarized relay 37 connected across the line. Such arrangements, however, are not shown in full as they do not strictly form part of the present invention and suitable circuits could readily be advised by those skilled in the art. It will be noted that when the digits TOL are dialled from the main exchange, the toll operator's position is reached by the transmission of the digits 5 and 2, switching-over then taking place immediately.

The case remains to be considered in which the subscriber wishes to set up a local connection, that is to say, a connection to a subscriber in the Vanguard satellite exchange. For convenience of description it will be assumed that, as before, when he removes his receiver, he takes into use successively the repeater R, the trunk line comprising conductors 59 and 60 and its associated switch SS, and the first code switch DS. The numerical equivalent of the exchange name Vanguard is 826 and consequently when the first digit is dialled the switch DS will be raised to the eighth level as before and will thereupon hunt to find a free register translator, for instance, that shown. The remaining digits 26 of the exchange name will then be set up on the code switch CS in the manner previously described, the wipers 203-206 being moved into engagement with the contacts 218-221. During the transmission of the second digit the earth through resistance 100 will be connected to the discriminating 130

relays 256—259 and as in the previous cases, relay 258 corresponding to the Vanguard exchange will be locked up.

When the complete exchange name has been dialled, the switch ICS moves into its third position and a circuit is then completed as follows: earth, wiper 164 and the third contact in its bank, wiper 170 and the first contact in its bank, lead 192, wiper 203, contact 218, lead 222, armature 267 and its front contact, lead 150, wiper 144, front contact and armature 138, armature 130 and its back contact, winding of relay 111 to battery. Relay 111 thereupon at its armature 112 opens the circuit for relay 46, while leaving relays 115 and 43 maintained energized in series. With these conditions at the repeater R, namely, relay 48 energized and relay 46 de-energized, a circuit is completed from earth, armature 35 and its back contact, armature 45 and its front contact, back contact and armature 48, winding of relay 15, interrupter contact and magnet 20 to battery. Relay 15 upon operating, at armatures 16 and 19 connects the speaking leads through the wipers 50 and 52 which are in engagement with a trunk extending to the preselected free local switch, at armature 18 completes a locking circuit for itself, opens the hunting circuit and feeds earth forward to wiper 51, and at armature 17 opens the circuit of relay 21. When relay 21 deenergizes, the outgoing loop over conductors 59 and 60 is opened at armatures 22 and 25, and accordingly the partially operated register translator is released as described above. The operation of armatures 16 and 19 also opens the circuit for line relay 5, which thereupon at armatures 6 and 8 opens the circuits of relays 43 and 46 and at armature 7 opens the circuit of relay 9 which, therefore, deenergizes after a short interval. The initial earth is thereupon removed from the release trunk conductor at armature 11, but before this takes place earth will have been fed back from the seized local switch over wiper 51 so that relay 15 and the switching relay of the subscriber's line switch are maintained operated. Relay 39 will deenergize shortly after its locking circuit is opened at armatures 44 and 47 so that all the apparatus originally operated in the repeater is restored to normal.

The above described switch-over operation takes place immediately after the termination of the third series of impulses, when it is definitely known that the call is to be completed locally; consequently when the subscriber dials again for the numerical digits, the interruptions produced by his calling device directly operate the line relay of the seized local switch, which is set in known manner, and one or more succeeding switches are then taken into use to complete the desired connection. In order that the number scheme may be kept uniform and to allow for growth, it

is probably desirable to employ four-figure numbers for designating subscribers connected to the various satellite exchanges, even though the size of an exchange does not exceed a thousand lines so that three digits would be sufficient. If three digits only or less were required, the extra impulses could be absorbed by the use of a digit-absorbing switch in the local switch train, which is probably the preferable solution, or alternatively by modifying the register translator slightly so that it did not switch until one or more numerical digits had been received so that the extra digits would be absorbed by the register translator. For instance the connection between the third and fourth contacts in the bank of wiper 164 could be opened on the operation of relay 258, though this might be objectionable as it would slow up the operation in the case of calls which did not require switching over. It will be seen from Fig. 4 that the code for obtaining access to the Vanguard exchange from any other exchange is 358, contact 221 being jumpered to terminal 224 to cause the switch OCS to move through its fourth position.

According to the invention, therefore, a very simple arrangement has been devised which does away with the necessity for number recording devices at satellite exchanges thus reducing the cost of the apparatus and simplifying the work of maintenance. It will be understood, of course, that the arrangement shown is only one example of carrying the invention into effect and that various modifications could be made if thought necessary or desirable. For instance, it might be found that it was not satisfactory for the switches L and T to select idle lines, but not seize them and in this case arrangements could be made whereby the lines were seized and if not required were released when relay 39 deenergized on the completion of dialling. Moreover since the subscriber only dials the letters TOL to reach the toll operator, the switch T need not hunt at all until it is taken into use as no special signals have to be transmitted to the toll operator's position.

It will be appreciated moreover that the number of relays in the marginal chain could be altered as desired, the limit being set by the necessity for a sufficient operating margin between the successive relays of the chain. Clearly also the arrangement of this marginal chain is not limited in its application to the particular circumstances shown.

What is claimed is:

1. A telephone system including satellite exchanges having their first numerical switches located in a main exchange and having calls within the satellite adapted to be completed entirely locally in which the number recording devices for determining whether a call shall be switched locally are located at the main exchange.

2. A telephone system including satellite exchanges and employing register controllers, in which numbers dialled by a subscriber attached to a satellite exchange are received by a register controller in the main exchange, and means in said register controller for sending back a special signal to the satellite in case the call is to be completed locally. 5 70
3. A telephone system employing register controllers seized by way of repeaters in which when the full number of digits have been dialled a distinctive signal is transmitted from the register controller to operate apparatus in the repeater, and means in said register controller for transmitting said signal as set forth. 10 75
4. In a telephone system, a satellite exchange and a main exchange, means comprising automatic switches in said satellite exchange only for completing a local connection, and a register sender in said main exchange for determining whether or not a call shall be completed locally. 20 80
5. In a telephone system, a satellite exchange and a main exchange, a register sender in said main exchange, means for transmitting the digits dialled by a calling subscriber whose line terminates in said satellite exchange to said sender, means in 25 85
- 30 said sender responsive to the receipt of said dialled digits for sending back to said satellite exchange a special signal in case the call is to be completed locally in said satellite exchange, and automatic step by step switches 35 90
- in said satellite exchange for completing the entire local connection independent of further control from said register sender. 95
6. In a telephone system, two exchanges, register senders in one exchange, a repeater 40 100
- 45 in the other exchange, relays in said repeater, means operative responsive to the seizure of said repeater for seizing one of said register senders, and means in said sender responsive to the registration of a complete telephone number for transmitting a distinctive signal from said sender to operate said relays. 105
7. In a telephone system, a first exchange and a second exchange, a trunk line connecting the first exchange with the second exchange, register senders in said second exchange, means responsive to a call originating in said first exchange for seizing one of said register senders over said trunk line, and means in said register sender responsive to the 50 110
- 55 registration of a complete telephone number for transmitting a signal back over said trunk line to the first exchange. 115
8. In a telephone system, a main exchange, a satellite exchange, a two-conductor trunk line connecting the satellite exchange with the main exchange, apparatus in said satellite exchange initially operated by a calling subscriber therat for connecting his line with said trunk line, apparatus in said main exchange operated over said trunk line to modi- 60 120
- fy the circuit connections at the main exchange end of said trunk line, means controlled by the modified circuit connections for disconnecting the calling line from said trunk line, and automatic switches in said satellite exchange then operated under control of the calling subscriber for completing the connection to the called line. 65 125
9. In a telephone system, a main exchange, a plurality of satellite exchanges associated with said main exchange by trunk lines, a register sender in said main exchange, said register sender common to said satellite exchanges and having means for causing circuit connections to be automatically made 70 130
- characteristic of the calling satellite exchanges when calls are to be set up in said satellite exchanges, means in said register sender responsive to a calling subscriber in one of said satellite exchanges dialling the office code corresponding to the satellite exchange in which the calling line terminates for effecting the release of said register sender, and automatic switches in said satellite exchange directly operated responsive to the calling subscriber dialling the remaining digits of the desired called line telephone number for completing the desired connection independent of said register sender. 75 85
10. In a telephone system, a main exchange, a plurality of satellite exchanges connected to said main exchange by trunk lines, register controllers in said main exchange, means for seizing one of said register controllers from one of said satellite exchanges, a circuit, means responsive to the seizure of said register controller for preparing said circuit to send back a special signal to said satellite exchange, means for setting said register controller in any one of a plurality of positions corresponding to said exchanges, and means for completing said circuit only in case said register controller has been set in a position corresponding to the calling satellite exchange. 80 90
11. In a telephone system, a main exchange, a plurality of satellite exchanges connected to said main exchange by trunk lines, register controllers in said main exchange, means for seizing one of said register controllers from one of said satellite exchanges, a circuit, means responsive to the seizure of said register controller for preparing said circuit to send back a special signal to said satellite exchange, means for setting said register controller in any one of a plurality of positions corresponding to said exchanges, means for completing said circuit only in case said register controller has been set in a position corresponding to the calling satellite exchange, and means responsive to the completion of said circuit for releasing said register controller. 85 95
12. In a telephone system, a main exchange, a plurality of satellite exchanges 90 100
- 105 110
- 115 120
- 125 130

connected to said main exchange by trunk lines, register controllers in said main exchange, means for seizing one of said register controllers from one of said satellite exchanges, a circuit, means responsive to the seizure of said register controller for preparing said circuit to send back a special signal to said satellite exchange, means for setting said register controller in any one of a plurality of positions corresponding to said exchanges, means for completing said circuit only in case said register controller has been set in a position corresponding to the calling satellite exchange, means responsive to the completion of said circuit for releasing said register controller, and automatic switches directly controlled by the calling subscriber independent of said register controller for completing a local connection.

13. In a telephone system, a main exchange, a satellite exchange, a toll exchange, a first trunk line connecting said main exchange with said satellite exchange, a second trunk line connecting said satellite exchange with said toll exchange, a register device in said main exchange, means responsive to a call by a subscriber in said satellite exchange for seizing said register device over said first trunk line, means for setting said register device in a position corresponding to said satellite exchange or said toll exchange, means responsive to either of said last setting means for releasing said register device, means operative in case said registering device was set in the position corresponding to said toll exchange for connecting the calling subscriber to said second trunk line extending to the toll exchange, and means in said satellite exchange operative responsive to the calling subscriber dialling the remaining digits of the desired called line's telephone number in case said registering device was set in the position corresponding to said satellite exchange for completing the connection to the called line.

14. In a telephone system, a main exchange, a plurality of satellite exchanges associated with said main exchange by trunk lines, an operator's position, local automatic switches in each of said exchanges, a register sender in said main exchange, means for completing local connections from a calling to a called subscriber in the same satellite exchange, for completing connections from a calling subscriber in one satellite exchange to a called subscriber in another satellite exchange, and for completing connections from a calling subscriber in one of the satellite exchanges to said operator's position, said means including only the switches in the satellite exchange in which the local connection is completed, the switches in the main exchange in the connection from one satellite exchange to another, and a switch in the satellite ex-

change originating the call to the operator's position, and means controlled by said register sender responsive to the digits dialled by the calling subscriber to complete any one of said connections for routing the call to the proper destination.

15. In a telephone system, a main exchange, a plurality of satellite exchanges associated with said main exchange by trunk lines, register controllers in said main exchange, a special switching device corresponding to each of said satellite exchanges in each of said register controllers, means for seizing any one of said register controllers and for operating the same from any one of said satellite exchanges, and means whereby the switching device in the seized register controller corresponding to the satellite exchange from which said register control was seized is automatically operated during the operation of said register controller.

16. In a telephone system, a trunk line comprising only two conductors, an impulse repeater, a register controller accessible to said repeater over said trunk line, and means in said repeater responsive to a signal transmitted from said register controller for conditioning said repeater to respond to supervisory signals.

17. In a telephone system, a calling line, a non-numerical switch, means responsive to the removal of the calling subscriber's receiver for seizing said switch, a plurality of trunk lines, means responsive to the seizure of said switch for causing said switch to preselect an idle one of said trunk lines, and means only effective responsive to a further operation by the calling subscriber for causing said switch to seize said preselected trunk line and make the same busy.

18. In a telephone system a calling line, a repeater, a first, a second, and a third non-numerical switch individual to said repeater, a first, a second, and a third group of trunk lines, means responsive to the removal of the calling subscriber's receiver for seizing said repeater, and means responsive to the seizure of said repeater for causing said first switch to seize an idle trunk line in said first group and for causing said second and third switches to preselect but not seize and make busy an idle trunk in said second and third groups, respectively.

19. In a telephone system, a calling line, a repeater, a first, a second, and a third non-numerical switch individual to said repeater, a first, a second, and a third group of trunk lines, means responsive to the removal of the calling subscriber's receiver for seizing said repeater, means responsive to the seizure of said repeater for causing said first switch to seize an idle trunk line in said first group and for causing said second and third switches to preselect but not seize and make busy an idle trunk in said second and third groups, respec-

tively, and means responsive to a further act by the calling subscriber for causing either said second or third switch to seize the pre-selected trunk line in its associated group.

5 20. In a telephone system a calling line, a repeater, a first, a second, and a third non-numerical switch individual to said repeater, a first, a second, and a third group of trunk lines, means responsive to the removal of the calling subscriber's receiver for seizing said repeater, means responsive to the seizure of said repeater for causing said first switch to seize an idle trunk line in said first group and for causing said second and third switches to preselect but not seize and make busy an idle trunk in said second and third groups, respectively, means responsive to a further act by the calling subscriber for causing either said second or third switch to seize the preselected trunk line in its associated group, and means responsive to said last means for releasing said first switch to free the seized trunk line in the first group.

25 21. In a telephone system, a main exchange, a plurality of satellite exchanges associated with said main exchange by trunk lines, a register controller in said main exchange common to said satellite exchanges, means responsive to a call for seizing and operating said register controller from any one of said exchanges, and means in said register controller for determining which one of the exchanges the call originated in.

30 35 22. In a telephone system, a main exchange, a plurality of satellite exchanges associated with said main exchange by trunk lines, a register sender in said main exchange, means responsive to a call from any one of said exchanges for seizing and setting said sender in the position corresponding to the called exchange, means in said sender for determining which one of said exchanges originated the call, and discriminating means in said sender for releasing said sender in case said sender is set in a position corresponding to the satellite exchange originating the call.

35 40 45 50 55 60 23. In a telephone system, a main exchange, a satellite exchange, trunk lines connecting the main exchange with said satellite exchange, branch lines, three switches in said satellite exchange, means in said satellite exchange responsive to a call for causing the first of said switches to seize an idle one of said trunk lines, and means in said main exchange for thereafter selectively operating either the second or the third of said switches over the seized trunk line to seize a desired one of said branch lines.

65 24. In a telephone system, a main exchange, a plurality of satellite exchanges, register senders only in said main exchange, means responsive to the initiation of a call by a calling subscriber in any one of said

satellite exchanges for seizing one of said senders in the main exchange, and means controlled by said seized sender responsive to impulses transmitted thereto by the calling subscriber for routing the call to any one of said exchanges in which the called line terminates.

70 25. In a telephone system, register senders, a talking circuit including a repeater, a switch, and a two conductor trunk line in serial relation over which talking connections to a called line are established, means for seizing one of said senders by way of said circuit, and means in said seized sender for transmitting a distinctive signal back over said circuit to operate apparatus in said repeater when the full number of digits of a called line have been dialled.

75 26. In a telephone system, register senders, a talking circuit including a repeater, a switch, and a two conductor trunk line in serial relation over which talking connections to a called line are established, means for seizing one of said senders by way of said circuit, and means in said seized sender for transmitting a distinctive signal back over only one talking conductor of said circuit to operate apparatus in said repeater responsive to the calling subscriber dialling the digits of a predetermined office code.

80 90 95 27. In a telephone system, register senders, a talking circuit including a repeater, a switch, and a two conductor trunk line in serial relation over which talking connections to a called line are established, means for seizing one of said senders by way of said circuit, means in said seized sender for transmitting a distinctive signal back over only one talking conductor of said circuit to operate apparatus in said repeater responsive to the calling subscriber dialling the digits of a predetermined office code, and means in said sender for transmitting a distinctive signal back over only the other talking conductor of said circuit to operate apparatus in said repeater in case the calling subscriber dialled the digits of a different predetermined office code.

100 105 110 115 120 125 130 28. In a telephone system, a first exchange, a second exchange, a repeater in said first exchange, a plurality of trunk lines extending from said repeater, the first of said trunk lines comprising only two talking conductors extending to said second exchange, means responsive to a call by a calling subscriber in the first exchange for seizing said repeater, means responsive to the seizure of said repeater for extending the connection over said first trunk line to the second exchange, means in said repeater controlled over only one of said conductors responsive to a predetermined act of the calling subscriber for disconnecting the calling subscriber from said first trunk line and for connecting said subscriber to another of said

trunk lines, and means in said repeater controlled over only the other of said conductors in case a different predetermined act is performed by the calling subscriber for causing the disconnection of the calling subscriber from said first trunk line and for connecting the calling subscriber to a third of said trunk lines.

29. In a telephone system, a chain of relays, a conductor normally connected to the first of said relays over a circuit including a pair of contacts on each of said relays, means for closing a circuit over said conductor to operate any number of said relays, the circuit for energizing the second of said relays including said conductor and contacts on all of said relays, the circuit for energizing the third of said relays including said conductor and contacts on all of said relays except the first relay, and the circuit for energizing the fourth relay including said conductor and contacts on all said relays except the first and second relays, and means controlled by each of said relays for closing a locking circuit for itself.

30. In combination, a plurality of relays, the first relay being arranged to operate responsive to a relatively small current flow, each succeeding relay requiring a larger current flow than the one immediately preceding it, an operating conductor extending to the first relay, means for setting up a current flow of desired predetermined strength over said operating conductor, contacts on the first relay operated if the first relay responds to the current flow for extending the operating circuit to the second relay, and contacts on each relay after the first and except the last operated if the relay responds to the current flow for extending the operating conductor to the succeeding relay.

31. In combination, a plurality of magnets, one of said magnets being arranged to operate responsive to a relatively small current flow, each succeeding magnet requiring a larger current flow for its operation than is required by the magnet immediately preceding it, an operating conductor, means for conditioning said conductor to transmit a current flow of desired predetermined strength thereover, and means for connecting said operating conductor to said magnets successively.

32. In combination, a plurality of magnets, one of said magnets being arranged to operate responsive to a relatively small current flow, each succeeding magnet requiring a larger current flow for its operation than is required by the magnet immediately preceding it, an operating conductor, means for conditioning said conductor to transmit a current flow of a desired predetermined strength thereover, means for connecting said operating conductor to said magnets successively, and means including a separate

circuit for maintaining any magnet in an operated condition that responds to the current flow over the said operating conductor.

33. In combination, a plurality of magnets, one of said magnets being arranged to operate responsive to a relatively small current flow, each succeeding magnet requiring a larger current flow for its operation than is required by the magnet immediately preceding it, an operating conductor, means for conditioning said conductor to transmit a current flow of a desired predetermined strength thereover, and means for connecting said operating conductor to said magnets successively beginning with the one which responds to the smallest current and continuing with the magnets in the order of their operating characteristics.

In witness whereof, I hereunto subscribe my name this 26th day of January, A. D. 1926.

FRANK TENCH.
